LANDING GEAR FOR TOY AIRPLANES

Harvey E. Shaeffer, Chicago, Ill., assignor to
Arvey Corporation, Chicago, Ill., a corporation
of Illinois

Application January 6, 1945, Serial No. 571,557

7 Claims. (Cl. 46—76)

1

This invention relates to toy airplanes and is more particularly concerned with improvements in landing gear for same.

This invention contemplates the provision of a landing gear for top airplanes which is simple and inexpensive in construction and which may be manufactured and sold as a kit of parts in un-assembled relation for assembly by boys, or others, interested in building model airplanes.

Briefly, this invention comprises a landing gear which may readily be assembled for attachment to the wing structure of a model airplane, and embodies a pair of sleeves having wheel supporting members telescopically engaged therein for yieldably resisting movement during landing of the plane.

This invention embodies other novel features, details of construction and arrangement of parts which are hereinafter set forth in the specification and claims, and illustrated in the accompanying drawings wherein:

Fig. 1 is a front elevational view showing a model airplane equipped with a landing gear embodying features of this invention.

Fig. 2 is an enlarged cross sectional view taken along the line 2—2 of Fig. 1.

Fig. 3 is a sectional view taken along the line 3—3 of Fig. 2.

Fig. 4 is a sectional view taken along the line 4—4 of Fig. 3.

Fig. 5 is a sectional view similar to Fig. 2 showing a modified form of this invention.

Fig. 6 is a sectional view taken along the line 6—6 of Fig. 5.

Referring now to the drawings for a better understanding of this invention and more particularly to Figs. 1 to 4 inclusive therein, the improved landing gear for toy airplanes is shown as comprising two similar units 4 and 5 each of which embody a sleeve 6 formed of paper or cardboard tubing and adapted to receive a wheel mounting shaft 7. The shafts 7 are preferably formed of wood and of a suitable diameter for telescopic sliding engagement with the inner wall of their respective sleeves 6. Each shaft 7 is engaged to its respective sleeve 6 by means of a piece of resilient wire 8, one end of which is offset laterally at 9 for engagement in apertures 10 formed in the sleeve and thence bent at 11 for engagement with the outer side of the sleeve. The other end of the wire is bent laterally at 12 to extend through an aperture 13 formed in the lower end of the shaft 7 and extends beyond same to provide a journal portion for a wheel 14 which is held against axial displacement there-

2

from by means of a washer 15 and a peened head 16. That portion of the wire 8 intermediate its ends is disposed rearwardly to provide a pair of arms 17 and 18 arranged at substantially right angles to each other and terminating at a loop portion 19. The upper ends of the sleeves 6 are adapted to be glued, or otherwise secured, to the wing structure 21 of a toy plane 22, although it is contemplated that the units 4 and 5 forming landing gear may be arranged otherwise than as shown in Figs. 1 and 2 in the drawings for attachment to other portions of a plane.

In the operation of the landing gear thus shown and described, a force applied against the lower portions of the wheels 14 acts to move the shafts 7 axially into their respective sleeves 6 against the yieldable resistance offered by the arms 17 and 18 of the wire members 8, and it will be noted that the wire members 8 also serve to maintain the wheels of the landing gear in parallel alignment during telescopic movement of the shafts 7 within their sleeves 6.

Figs. 5 and 6 illustrate a modified form of landing gear unit embodying features of this invention in which a spring member 24 is helically wound at 26 around the sleeve 6 and having its lower end extending downwardly at 27 parallel with the wheel mounting shaft 7 and offset at 28 to extend through an aperture 29 provided in the lower end of the shaft 7. The offset portion 29 is of sufficient length to provide a journal for the wheel 14 which is secured against axial displacement therefrom in the manner heretofore described in connection with Figs. 1 to 4. The upper end of the spring member 24 is secured to the sleeve 6 by means of a pin 30 extending transversely through the sleeve 6 between the upper convolutions of the helical portion 26. In this form of the invention, it will be observed that the helical portion 26 of the spring member 24 serves to yieldably resist telescopic movement of the shaft 7 relative to its sleeve 6.

In several of the forms of this invention, it will be noted that the several parts may be inexpensively formed of cardboard, wood and the like, and readily assembled with a piece of spring wire to form a landing gear unit in which the wheel mounting shaft is yieldably resistant to telescopic movement into its mounting sleeve. While the landing gear has been shown and described as comprising an assembled structure, it is contemplated that the several parts thereof may be manufactured and sold in the form of a kit for assembly by model makers and others.

While this invention has been shown in several forms, it is obvious to those skilled in the art that it is not so limited but is susceptible of various changes and modifications without departing from the spirit and scope of the claimed invention.

I claim as my invention:

1. In a model airplane, a wing structure having transverse ribs, a pair of tubular sleeves having their upper ends secured to said transverse ribs, wheel supporting members telescopically mounted in said sleeves, wheels journaled on said supporting members, and resilient wire means for yieldably resisting axial and rotational movement of said wheel supporting members relative to their respective sleeves, one end of each resilient wire means serving as a journal for a wheel.
2. A landing gear for model airplanes comprising a pair of tubular sleeves, wheel supporting members telescopically mounted in said sleeves, wheels journaled on said supporting members, and resilient wire means for yieldably resisting axial and rotational movement of said wheel supporting members relative to their respective sleeves, one end of each resilient wire means serving as a journal for a wheel.
3. A landing gear kit for model airplanes comprising a pair of tubular sleeves, wheel supporting members for telescopic mounting in said sleeves, wheels for journaled engagement on said supporting members, and resilient wire means for yieldably resisting axial or rotational movement of said wheel supporting members relative to their respective sleeves, one end of each resilient wire means serving as a journal for a wheel.

4. In a device of the character described, a pair of members disposed for relative telescopic movement, a wheel journaled on one of said members, resilient wire means for yieldably resisting relative axial and rotational movement of said members, one end of each resilient wire means serving as a journal for a wheel.
5. In a device of the character described, a sleeve, a wheel, a wheel supporting shaft for axial movement within said sleeve, and resilient wire means for yieldably resisting axial and rotational movement of said shaft with respect to said sleeve, one end of each resilient wire means serving as a journal for a wheel.
- 10 6. In a device of the character described, a sleeve, a wheel, a wheel supporting shaft for axial movement within said sleeve, and a V-shaped resilient wire for yieldably resisting axial and rotational movement of said shaft with respect to said sleeve, said resilient wire having its ends formed for engagement with said sleeve and shaft, one end of said resilient wire serving as a journal for said wheel, and the other end of said wire serving as a stop to limit inward movement of said shaft.
- 15 7. In a device of the character described, a sleeve, a wheel, a wheel supporting shaft for axial movement within said sleeve, and resilient wire means for yieldably resisting axial and rotational movement of said shaft with respect to said sleeve, said resilient wire means comprising a helical compression spring having its ends connected to said sleeve and shaft, one end of said wire means serving as a journal for said wheel.
- 20 8. In a device of the character described, a sleeve, a wheel, a wheel supporting shaft for axial movement within said sleeve, and resilient wire means for yieldably resisting axial and rotational movement of said shaft with respect to said sleeve, said resilient wire having its ends formed for engagement with said sleeve and shaft, one end of said resilient wire serving as a journal for said wheel, and the other end of said wire serving as a stop to limit inward movement of said shaft.
- 25 9. In a device of the character described, a sleeve, a wheel, a wheel supporting shaft for axial movement within said sleeve, and resilient wire means for yieldably resisting axial and rotational movement of said shaft with respect to said sleeve, said resilient wire means comprising a helical compression spring having its ends connected to said sleeve and shaft, one end of said wire means serving as a journal for said wheel.
- 30 10. In a device of the character described, a sleeve, a wheel, a wheel supporting shaft for axial movement within said sleeve, and resilient wire means for yieldably resisting axial and rotational movement of said shaft with respect to said sleeve, said resilient wire having its ends formed for engagement with said sleeve and shaft, one end of said resilient wire serving as a journal for said wheel, and the other end of said wire serving as a stop to limit inward movement of said shaft.
